ICE TRAY

Robert Lay Hallock, Larchmont, N. Y.

Application October 24, 1940, Serial No. 362,553

7 Claims. (Cl. 62—108.5)

My invention relates to ice trays for refrigerators and more particularly to an improved tray having a force multiplying tray release. Such tray release devices have heretofore been of a construction having journalled or close sliding parts. Particularly in the case of levers when so used it has been the practice to mount a journal on the tray and mount the lever on the journal so that the separating force is carried through the journal. The force for separating an ice bond between an ice tray and a freezing surface is large and the consequent stress on the lever journal is large. Also such a journal cannot be lubricated.

The object of my invention is to simplify structure of this kind and to do away with the journal or other close contact mounting through which force is transmitted when the leverage action is used in severing the ice bond. Furthermore I aim to apply the forces more directly and over surfaces such that the unit stress is reduced.

The nature of my invention will be apparent from the following description taken in conjunction with the accompanying drawing forming part of this specification and of which:

Fig. 1 is a front view of a tray embodying the invention disposed in the freezing unit of a refrigerator;

Fig. 2 is a vertical sectional view taken on line 2—2 of Fig. 1; and

Fig. 3 is a partial bottom view of my improved tray.

Numerical 10 represents an evaporator or freezing unit of a refrigerator which is cooled to sub-freezing temperatures by a refrigerating system of any suitable kind. Resting on a shelf 11 of freezing unit 10 is an ice tray 12.

Ice tray 12 includes a pan or tray body 13 preferably made of metal such as aluminum and adapted to hold water to be frozen. The tray also includes a leverage device for severing an ice bond between the tray body and the cold top surface of shelf 11. The leverage device, generally designated by numeral 15, is preferably disposed at a corner of the tray and the tray is preferably of such thin metal that a peeling action takes place beginning at a corner of the tray body.

Attached to the front side of the tray body is a bearing plate 16 of materially thicker stock than the tray body itself. Bearing plate 16 conforms to the contour of the tray body and may be spot-welded thereto. The tray body and bearing plate are dished at 17 to provide a ful-

crum pocket. Only the middle part of the bearing plate extends into pocket 17. Lateral parts of the bearing plate are formed to be spaced from the tray body and are formed with projections 18, one on each lateral part, which extend toward each other and form a loose mounting for the lever 20.

Lever 20 is a dished stamping having a top wall and upstanding sides 21. Sides 21 are provided with holes 22 materially larger than the projections 18 and into which these projections pass. The parts are so formed that when assembled and with the tray placed on shelf 11, lever 20 also rests with its lower edge on shelf 11. In this position projections 18 are midway of holes 22 and the parts can be so disposed that there is clearance between the projections 18 and the lever 20 and clearance between the lever and the bearing plate. Such position is shown in Fig. 2. Even if the lever touches the projections or the tray body, there is no support by virtue of the mounting due to the clearance between the lever and the mounting on the one hand and the middle part of the bearing plate on the other hand. It will be seen that the space between the mounting and the central part of the bearing plate is much wider than the thickness of the part of the lever therebetween. The tray body and the lever rest independently on the shelf, the mounting and lever holes merely providing a loose connection to retain the parts in operative but inactive relation like links of a chain when unstressed. The upper part of the lever is cupped to pass into the recess formed at 17 and to provide a rounded fulcrum bearing surface when the lever is raised. The handle end of the lever may be provided with a plastic cap 24 for contact with the finger of the operator.

To release the tray from the shelf, the lever 20 is lifted. Due to the clearances between the lever and the central part of the bearing plate and the mounting respectively, the initial movement is, in a sense, a lost motion in which the lever pivots about the edge remote from part 24 in contact with the shelf. When the top arched portion of the lever contacts the bearing plate, the lever acts as a first class lever with the fulcrum in the depression formed at 17; the short arm being between the fulcrum and the shelf, and the long arm being between the fulcrum and the part 24. Then upward force against part 24 causes force multiplication to pry the tray from the shelf by peeling action beginning at the corner of the tray. In this leverage action, the lever force is applied directly to the bearing plate

and the reaction is against the shelf and there is no force exerted on the mounting whatever. Since the mounting transmits no force, it need not be strong and there are no pivot joints or other devices having any journal action to bind or freeze or take stress in small parts. The force is spread over a considerable area due to the complementary curvatures and width of the contacting parts of the lever and the bearing plate.

As will be apparent from the drawing, the bearing plate and lever can be made of two sheet metal stampings. The bearing plate is simply cut and formed to provide both the bearing surface and the mounting. The lever can be made as merely a cupped stamping with two holes in the sides. The mounting need not be strong since no force is exerted on it. No matter how much frost builds up, the lever is easily actuated.

The same lever and bearing plate may be used in principle without having the lever rest on the same surface as the tray body. For example, the lever may rest on a higher surface with the bearing plate attached to the side of the tray. However, I prefer to have the force projected directly against the tray body or a reinforcement such as plate 16 directly conforming to the contour thereof.

It will be seen that my improved tray release is sturdy though simple in construction and that the lever is a unitary part of the tray and that journal rotation as in pivots or hinges of ordinary kind has been eliminated.

I claim:

1. In an ice tray for a refrigerator, a tray body adapted to rest on a supporting surface, a bearing plate mounted on said tray body, a mounting fixed with respect to said bearing plate, and a lever loosely held to said tray by said mounting and adapted to lie against said supporting surface when the tray rests thereon with clearance between the lever and the mounting and clearance between the lever and the bearing plate, said lever having contact with said bearing plate when raised and contacting said surface to exert force multiplication for separating said tray body from said surface without stress on the mounting.

2. In an ice tray for a refrigerator, a tray body for use in a part of a freezing unit, a bearing plate mounted on said tray body, a mounting fixed with respect to said tray body, and a lever loosely held to said tray by said mounting and adapted to lie against a surface of said freezing unit when the tray is in position for freezing with clearance between the lever and the mounting and clearance between the lever and the bearing plate, said lever having fulcrum contact with said bearing plate when raised and contacting the freezing unit to exert a leverage for severing any ice bond which may be formed at the bottom of said tray body without force being exerted on or through the mounting.

3. The combination with a cooling element having a shelf or support, of a tray body adapted to rest on the support and having side walls and open at the top, one of the side walls intermediate the top and bottom edges thereof being shaped to provide a substantially horizontal wall portion spaced from the shelf, and a member pivotally connected to said side wall of the tray in

the vicinity of the horizontal wall portion and operable to separate the tray from the support, said member being so arranged and connected on the tray that all of the force to separate the tray from the support is primarily transmitted through a part of the member with substantially no force being transmitted through the pivotal connection.

4. The combination with a cooling element having a shelf or support, of a tray body having a bottom and vertical walls and adapted to rest on the support, and mechanism on the tray to exert a separating force between the tray and shelf to raise the former with respect to the latter, said mechanism including a part turnably mounted on one of said vertical walls against which ice is adapted to be frozen within the tray, said mechanism being so constructed and mounted on said vertical wall that, when the separating force is produced to break an ice bond that may be formed between the bottom of the tray and the support, substantially no force acts on said mounting whereby straining of the said mounting is substantially avoided.

5. In an ice tray for a refrigerator, a tray body adapted to have contact with a cold surface between which body and cold surface an ice bond may be formed, said tray body having a side wall, a part on the exterior of said side wall providing a pivotal support for a lever, and a lever pivotally mounted on said support, said parts being so constructed and arranged, and particularly the clearance between said lever and its pivotal support being such, that raising one end of said lever causes the other end of said lever to fulcrum on said cold surface, and an intermediate part of said lever to bear against said tray to effect severance of an ice bond, while at the same time said lever substantially clears its pivotal support so that substantially no force is exerted on the support.

6. In an ice tray for a refrigerator, a tray body having a bottom and upright side walls, a support having a cold surface, said tray body adapted to have contact with said cold surface between which body and surface an ice bond may be formed, a lever contacting the tray and support, and a part on the tray to hold the lever adjacent one of the upright walls outside of the tray, said elements being so constructed and associated that said lever can be rotated with respect to said one upright wall while contacting the tray and support to exert an ice bond breaking force on said tray body without exertion of force on said lever holding part.

7. The combination with a cooling element having a shelf or support, of a tray body adapted to rest on said support and having a side wall dished inward to form a pocket in the exterior surface thereof, which pocket has a wall portion substantially horizontal and spaced from said support, a part secured to said tray body in the vicinity of said pocket, and a turnable member carried by said part, said elements being so constructed and arranged that said member is operable to produce a separating force between said substantially horizontal wall portion and said support while exerting a substantially zero force of action or reaction on said part.
